ATTORNEY

UNITED STATES PATENT OFFICE

HARRY F. WOERNLEY, OF WILKINSBURG, PENNSYLVANIA, ASSIGNOR, BY MESNE ASSIGNMENTS, TO CARDWELL WESTINGHOUSE COMPANY, OF CHICAGO, ILLINOIS, A CORPORATION OF DELAWARE

FRICTION DRAFT GEAR

Application filed March 2, 1928. Serial No. 258,624.

This invention relates to draft rigging for railway cars and more particularly to friction draft rigging for use especially in passenger cars.

The principal object of my invention is to provide an improved draft rigging of the above type which will effectively cushion ordinary draft and buffing forces incident to the operation of a train of coupled cars before the friction elements are caused to operate to cushion extraordinary heavy draft and buffing forces.

In the accompanying drawing; Fig. 1 is a longitudinal sectional plan view of the draft rigging, the several parts thereof being shown in their normal positions; Fig. 2 is a like sectional view showing the several parts of the draft rigging in their extreme initial cushioning positions in buffing, just before the friction elements are caused to operate; and Fig. 3 is a detail sectional view, taken on the line 3—3 of Fig. 1, showing one of the friction elements anchored to the casing.

The draft rigging shown in the drawing may comprise a hollow rectangular casing 1 having front and rear sections 2 and 3 respectively, which are secured together by bolts 4 or any other desired means.

The front section 2 contains alternated friction plates 5 and 6 which are disposed at opposite sides of a wedging mechanism, the plates 5 being wedge-shaped and anchored to the section 2, and the plates 6 having parallel friction faces, there being relative longitudinal movement between the plates 5 and 6 when the rigging is subjected to secondary or extraordinarily heavy buffing stresses or draft strains.

Contained in the section 3 are springs 7, 8 and 9, the rear ends of which seat on a movable spring seat or follower member 10 having a central portion 11 which normally extends through an opening in the rear wall 12 of the section and abuts a rear follower 13 which is engaged by the rear portion of the draft yoke 14. It will be understood that if desired the member 10 and follower 13 may be made integral. The forward end of the spring 7 seats on an inwardly extending flange 15 forming the rear end of the sec-

tion 2. The outer ends of the springs 8 and 9 seat on a follower 16 contained in the section 2 of the casing, which follower engages the rear ends of the friction plates 6.

The wedging mechanism comprises longitudinally disposed wedge blocks 17 and 18 having opposed wedging faces adapted to engage corresponding wedging faces of wedge blocks 19 and 20, the outer faces of which blocks 19 and 20 engage the inner friction plates 6. The outer end of the wedge block 17 abuts a front follower 21 and has a rearwardly extending stem 22 having an opening formed therein through which a locking key 23 passes, the ends of said key passing through slots formed in the top and bottom walls of the section 2. The rear end of the wedge block 18 engages the follower 16.

The locking key is for the purpose of maintaining the several parts of the rigging connected to the casing 1, under initial compression, and to lock the key against accidental movement in the direction of its length, a pin 24 is provided which extends through a longitudinal bore in the stem 22 into locking engagement with the key and is maintained in such engagement by the pressure of a spring 25 contained in a recess formed in the follower 16.

When the draft rigging is in its normal release condition, the front follower 21 abuts front draft lugs 26, and the rear follower 13 abuts rear draft lugs 28, all of which lugs are secured to the draft sills (not shown) of the car in the usual manner.

In operation, when the draft rigging is subjected to draft strains transmitted through the shank 27 of the usual car coupler, the draft yoke 14, which at its forward end is attached to the shank 26 will, together with the follower member 10, be caused to move forward against the pressure of the springs 7, 8 and 9 and these springs, during the movement of the member 10 are adapted to resist and cushion ordinary service shocks incident to the pulling of the car. The initial frictional resistance offered by the wedging mechanism, plates 5 and 6 and casing 1 is sufficient to withstand the outward pressure of the spring 7 against the casing 1, so that as

the follower member 10 is moved forward, the casing 1 will be maintained stationary.

Should the draft strain on the yoke 14 be greater than can wholly be resisted by the pressure of the springs 7, 8 and 9 acting through the medium of the follower member 10, the rear follower 13 will engage rear end wall 12 of the casing and cause said casing, together with the wedge-shaped plates, to move forward as a unit, thus further compressing the springs 8 and 9. It will here be noted that when the member 10 has been moved inwardly until the follower 13 engages the rear wall 12 of the casing, the spring 7 will not be compressed further when the casing is moved forward. As the casing and the plate 5 are moved forward and the springs 8 and 9 compressed, the frictional resistance set up between the wedging mechanism and the plates 5 and 6 is increased until the rigging is fully compressed or the draft strains are cushioned.

In the release movement of the draft rigging the combined pressures of the springs 7, 8 and 9, acting upon the follower member 10, cause the member 10, together with the draft yoke 14 and rear follower 13 to move rearwardly relative to the casing 1 until such time as the member 10 again engages the rear wall 12 of the casing, when the combined pressures of the springs 8 and 9 will cause the casing, plates 5, spring 7, member 10 and draft yoke 14 to move rearwardly as a unit relative to the plates 6 and wedging mechanism, until the rear follower 13 again abuts the rear draft lugs 28. This movement of the casing and plates 5 and the relieving of the pressure of the springs 8 and 9 permits the wedging mechanism to assume its release position in which the initial compression hereinbefore mentioned again resists the pressure of the spring 7.

When the draft rigging is subjected to buffing stresses or shocks transmitted through the coupler shank 27 and front follower 21, the wedging mechanism, friction plates 5 and 6 and casing 1 will be moved rearwardly as a unit, and as the member 10 is in abutment with the rear follower 13 the relative movement between the casing and member 10 will cause the springs 7, 8 and 9 to be compressed, thus cushioning primary buffing shocks. If the buffing stresses or shocks are of such magnitude that they cannot be resisted by the pressure of the springs, the casing abuts the follower 13, causing the friction elements to move into cushioning operation, as hereinbefore described in connection with heavy draft strains.

In releasing the draft rigging after a secondary or extraordinary buffing shock, the combined pressure of the springs 7, 8 and 9 will cause the casing 1, plates 5 and 6, and wedging mechanism and front follower 21, to move forward relative to the member 10,

until the rear wall 12 of the casing engages the member 10 when the pressure of the springs 8 and 9 will cause the plates 6 and wedging mechanism to operate to their release positions as shown in Fig. 1 of the drawing.

While one illustrative embodiment of the invention has been described in detail, it is not my intention to limit its scope to that embodiment or otherwise than by the terms of the appended claims.

Having now described my invention, what I claim as new and desire to secure by Letters Patent, is:—

1. In a shock absorbing mechanism, the combination with a casing comprising a forward section and a rear section, said sections being rigidly connected together, of a follower loosely mounted in the rear end portion of the rear section of the casing, a spring interposed between and engaging said follower member and the rear portion of the forward section adapted to cushion primary draft and buffing shocks, friction means mounted in said forward section for cushioning secondary draft and buffing shocks, a follower plate loosely mounted in said forward section and engaging said friction means, and a spring interposed between and engaging said followers yieldably resisting relative movement between said casing and friction means in cushioning secondary draft and buffing shocks.

2. In a shock absorbing mechanism, the combination with a casing, of a follower member loosely mounted in the rear end portion of said casing, a spring interposed between and directly engaging said follower member and casing adapted to cushion primary draft and buffing shocks, friction cushioning means mounted in the forward end of the casing for cushioning secondary draft and buffing shocks, said friction cushioning means including longitudinally movable plates, a follower member loosely mounted in said casing and engaging the inner ends of said plates, and a spring interposed between and engaging said follower members for opposing relative movement between said friction means and casing when the shock absorbing mechanism is subjected to secondary draft and buffing shocks.

3. In a shock absorbing mechanism, the combination with a casing, of a follower member loosely mounted in the rear end portion of said casing, a spring interposed between and directly engaging said follower member and casing adapted to cushion primary draft and buffing shocks, friction cushioning means mounted in the forward end of the casing for cushioning secondary draft and buffing shocks, a follower member loosely mounted in the forward end of the casing and engaging said friction cushioning means, and a spring interposed between and

engaging both of said follower members for opposing relative movement between said friction cushioning means and casing in cushioning secondary draft and buffing shocks, the first mentioned spring being ineffective to resist said secondary draft and buffing shocks.

4. In a shock absorbing mechanism, the combination with a casing, of a follower member loosely mounted in the rear end portion of said casing, a spring interposed between and directly engaging said follower member and casing adapted to cushion primary draft and buffing shocks, friction cushioning means mounted in the forward end of the casing for cushioning secondary draft and buffing shocks, said friction cushioning means comprising longitudinally movable friction plates, wedging means operative to impress lateral pressure on said plates when the shock absorbing mechanism is subjected to secondary draft and buffing shocks, a follower member loosely mounted in the forward end of the casing and engaging the rear ends of said plates and wedging means, and a spring interposed between said follower members opposing relative movement of said casing and friction means.

30 In testimony whereof I have hereunto set my hand.

HARRY F. WOERNLEY.
